UNITED STATES PATENT OFFICE.

GEORGE H. FORSYTH, OF CHICAGO, ILLINOIS, ASSIGNOR TO WAUGH DRAFT GEAR COMPANY, A CORPORATION OF ILLINOIS.

DRAFT AND BUFFING MECHANISM FOR RAILWAY-CARS.

1,123,511.

Specification of Letters Patent.

Patented Jan. 5, 1915.

Application filed September 27, 1906. Serial No. 336,476.

To all whom it may concern:

Be it known that I, GEORGE H. FORSYTH, a citizen of the United States, residing at Chicago, in the county of Cook and State of Illinois, have invented certain new and useful Improvements in Draft and Buffing Mechanism for Railway-Cars, of which the following is a specification.

This invention relates generally to the art 10 of draft and buffing mechanism for railway cars, and pertains more especially to improvements in that class or type of such devices which require a comparatively wide range of lateral or angular movement of 15 such parts on account of short and sharp curves in the track.

More specifically, the invention relates to the provision of means whereby the safety chain connections between adjacent cars 20 may be supported without danger of breaking or cramping on curves, and whereby also the pull exerted on the safety chains in case of accidental uncoupling is exerted through the resistance medium of the draft- 25 rigging, thus lessening liability of breakage of the safety chains through sudden shock.

A simple mechanical embodiment of the invention is illustrated in the accompanying 30 drawings, wherein,—

Figure 1 is a plan view of a wide clearance draft and buffing rigging having my improvements applied thereto, with so much of the underframe and truck of a rail- 35 way car as suffices to make clear the application of the invention; Fig. 2 is a longitudinal vertical sectional view of the same; Figs. 3 and 4 are, respectively, plan and side elevational details of the forward end of 40 the draft rigging, showing the draft rigging proper, and showing the manner and means of connecting the safety chains.

Referring to the drawing, 7 may designate the longitudinal sills of a car under- 45 frame; and 8 may designate the transverse I-beams forming hangers or carry-irons for the draft and buffing mechanism. Somewhat inwardly of the forward end of the car frame is located what I term the draft 50 rigging, the same comprising, in the simple form shown, the usual stop castings 9, front and rear follower shells 10 and 11, draft springs 12 housed in said shells, and the usual yoke or drawbar extension 13, the 55 forward end of which latter is pivotally

connected as by a pivot-bolt 14, to the rear end of a drawbar 15, which latter is herein shown as of considerable length, and may consist of a single bar, or of a plurality of sections connected end to end. 60

Secured to and embracing the outer portion of the draw-bar, slightly in rear of the coupler head 16, is a buffer-supporting frame or casting 17, with the specific details of which the present invention is not 65 concerned, but which affords the housing and support for a pair of buffer springs (not shown) that are operatively connected by forwardly projecting stems 18 with a buffer-plate 19, which latter is supported 70 thereby normally substantially coincident with the forward end of the coupler head, as shown. It will thus be seen that the buffing mechanism is wholly carried by the drawbar, and, of course, partakes of the 75 lateral or angular movements of the draw- 80 bar in passing over curved track. The specific construction and style of mounting of the draft-rigging, drawbar and buffing mechanism as shown and described is in no wise essential to the present invention, 85 which is concerned more particularly with a novel manner and means of mounting and supporting the safety chain connections that underlie the ends of the cars; the leading feature of my invention in this respect residing in an elastic connection of the safety chains to the car-body, which connection is preferably through the resistance medium of the draft-rigging. 90

Referring first to the safety chains, 20 designates these elements, and 21 designates inwardly extending link rods therefrom, which link rods, in the form shown in Figs. 1 and 2, are hooked onto a clevis 22 that is 95 pivotally mounted on the pivot-bolt 14 connecting the inner end of the drawbar to the yoke of the draft rigging, from which it will be seen that the safety chain connections pivot on and swing from the same center of lateral movement as the drawbar, and are also directly connected to the draft rigging, so that any pull thereon, due to breakage or disconnecting of the couplers, is imparted directly to the draft rigging, and 105 this under a cushioning effect tending to prevent breaking of the chain and links. Figs. 3 and 4 illustrate a modification of the anchoring means of the safety chains, wherein the free ends of the links 21 of the 110

safety chains are connected to the ends of a U-shaped rod or bar 23, lying in a transverse slot or groove in the inner end of the drawbar shank.

5 I claim:

1. The combination with a car-body and a draft-rigging, of a safety chain connected to said car-body through the resistance medium of said draft-rigging.

10 2. The combination with a draft-rigging and a drawbar pivoted in advance of said draft-rigging, of a safety chain connection adapted to swing radially on a pivot substantially coincident with that of the drawbar.

15 3. The combination with a draft-rigging

and a drawbar pivoted in advance of said draft-rigging, of a safety chain connection pivotally connected to the forward end of the draft-rigging and axially coincident 20 with the pivot of the drawbar, whereby said connection exerts its pull through the draft-rigging.

4. The combination with the fixed draft rigging of a car including a yoke, of a draw 25 bar and a safety chain connection both attached to the yoke to swing upon a common pivot, substantially as described.

GEORGE H. FORSYTH.
